UNITED STATES PATENT OFFICE.

ISABELLA MORLAND KING, OF BONNIE BRAE, RICHMOND HILL, ENGLAND.

PORTABLE FOLDING COOKING AND HEATING OVEN.

1,262,210.

Specification of Letters Patent.

Patented Apr. 9, 1918.

Application filed February 14, 1917. Serial No. 148,675.

To all whom it may concern:

Be it known that I, ISABELLA MORLAND KING, a subject of the King of Great Britain and Ireland, and residing at Bonnie Brae, 5 Richmond Hill, in the county of Surrey, England, have invented Improvements in Portable Folding Cooking and Heating Ovens, of which the following is a specification.

10 My invention relates to portable, folding, cooking, and heating oven, of the type which will cook with an ordinary gas ring or in front of a gas or electric stove or an open fire grate and is a modification of the invention described in my application, Serial 15 No. 130745, filed 11th November 1916.

The said application sets forth an oven of the class described above having a particular construction, combination, and arrangement of hinged sheets to form the oven with supporting feet and trays with tray supports of wire.

According to the present invention instead of supporting the trays as in Serial No. 25 130745 I provide sheets or wings made of metal or other suitable material which are detachably associated with the walls *a*, these sheets being provided with strips of metal to form shelves on which the trays rest.

30 The accompanying drawing shows my improvement and is similar to the figure I re-

ferred to in Serial No. 130745 like numerals being used.

Attached to the main walls *a* of the oven are two sheets or strips *O* of metal or suitable material forming wings which may be framed in wire for strengthening. Secured to these wings *O* on their inner sides are a number of strips *p* to form shelves upon which the trays *f* rest. The wings *O* are 40 preferably hinged at *q* to the walls *a* in such a manner as to be removable and free to swing inwardly to fold in when the oven is closed for transport. Stops *r* in the form of angle pieces are attached to the sheets 45 or wings *O* and engage the walls *a* when the wings *O* are open, these being provided for the purpose of preventing the wings from opening out beyond the required distance.

50 What I claim is:—

A folding cooking rack, comprising a main plate and side plates hinged thereto, binding wires for the edges of the plates being extended to form curved feet and handles, wings hinged to the side plates to fold substantially parallel therewith, and provided with co-operating means for holding a tray upon adjacent wings.

55 ISABELLA MORLAND KING.
